United States Patent Office.

JAMES S. ATTERBURY AND THOMAS B. ATTERBURY, OF PITTSBURG,
PENNSYLVANIA.

Design No. 4,225, dated July 19, 1870.

DESIGN FOR A JELLY-CUP.

The Schedule referred to in these Letters Patent and making part of the same.

To all whom it may concern:

We, JAMES S. ATTERBURY and THOMAS B. ATTERBURY, of Pittsburgh, in the county of Allegheny and State of Pennsylvania, have invented and produced a new and original Design for a Jelly-Cup, of which the following is a specification, reference being had to the accompanying drawings making part of the same, in which—

Figure 1 is a side view of the design.

Figure 2 is a bottom view.

Similar letters of reference indicate corresponding parts in the several figures.

The cup is circular when taken horizontally at any point from its base to its upper margin, as shown in fig. 2.

When taken vertically the cup presents convex

bulging sides, the swell extending from the point *a* to the point *b*.

The lower portion of the cup is considerably smaller than the upper portion; consequently the cup presents an upwardly-flaring form, as shown in fig. 1 of the drawings.

The jelly-cup is preferably made of glass, and above the curved portion it may be elongated to any extent desired without changing the design represented.

We claim as our invention—

The design for a jelly-cup, as described and shown.

J. S. ATTERBURY.

T. B. ATTERBURY.
